UNITED STATES PATENT OFFICE

THOMAS L. RIVERS, OF MONTCLAIR, NEW JERSEY.

HAME-TUG.

SPECIFICATION forming part of Letters Patent No. 330,517, dated November 17, 1885.

Application filed August 11, 1885. Serial No. 174,146. (No model.)

To all whom it may concern:

Be it known that I, THOMAS L. RIVERS, a citizen of the United States, residing at Montclair, in the county of Essex and State of New Jersey, have invented a new and useful Improvement in Hame-Tugs, of which the following is a specification, reference being had to the accompanying drawings, and in which—

Figure 1 is a plan view of a hame-tug embodying my improvements with the leather covering detached partially. Fig. 2 is a longitudinal section on the line $x-x$ of Fig. 1. Fig. 3 is a detached perspective view of one of the sections. Fig. 4 is a detailed view of the end plate. Fig. 5 is a detailed view of the tongue.

Like letters of reference in the several drawings denote corresponding parts.

Referring by letter to the drawings, A designates a hame-tug embodying my invention and composed of a series of sections, B, a trace-carrier, C, and a trace-plate, D. The trace carrier and plate C D are of the form shown in my pending application filed May 20, 1885, Serial No. 166,293, and need not be here specifically described, the invention in the present instance relating more particularly to the peculiar connection between the sections of the tug. Each of the sections B comprises a single casting and is made skeleton in form for strength and lightness.

I will now describe the particular construction of one of the sections, but it will be understood that each section B is constructed in accordance with the following description.

The section is rounded on its upper surface, as at c , and has cast therewith an upwardly-projecting frame, d , preferably rectangular or square in form, and provided with an opening, d' , having notches d'' at one end communicating therewith, in which openings are adapted to fit the engaging shoulder e and flanges e' , respectively, of the trace-plate D, which is provided with a spring-actuated pivoted latch, D', and is connected at one end to the trace to connect said trace to any one of the recesses d d'' , thus accommodating traces of different lengths. At one end the section B is cut away or bifurcated, as at f , and provided with notches f' at their inner portions, the arms of the bifurcated or cut-away portion f being connected together by

a cross-bar, f'' , arranged in a plane below the upper surface of said arms and parallel with the lower surface or edges of the section B. At its front end the section is provided with a projecting tongue, g , parallel with the upper surface of the casting and at the middle thereof. On the under or lower surface said tongue is provided with a lug or shoulder, h , at its side edges with an outwardly projecting flange, i , arranged below the upper edge thereof, and at its front edge said tongue is provided with a tapering flange, j , also arranged below the plane of its upper edge and meeting the side flanges, i , which are made tapering from their rear edges to a point where they merge into the flange j .

From the foregoing description it will be observed that each section is provided with a socket at one end for the reception of the tongue of the adjacent section, and at its opposite end with a tongue which engages the socket of the adjacent section. A firm, strong, and flexible connection is thus provided, and to this particular construction I attach importance, as therein lies the gist of the present invention.

To connect the sections together it is only necessary to fit the lugs i between the notches f' of the tongue, and then bring the sections in a line with each other, the sections being arranged at right angles with relation to each other when fitting the flanges of the tongue in the recesses f' of the socket of the adjacent section.

When the sections are arranged in a horizontal position, it will be observed that the tongue lies wholly within the socket of the adjacent section and parallel with the upper and lower surfaces thereof, while at the same time the necessary movement or flexibility between the sections is permitted.

The upper rounded faces of the sections are covered or inclosed within a sheath of leather or other suitable material, k , the flanges surrounding the recesses d d'' projecting through said sheath to permit the trace-plate to be readily engaged and detached therefrom. The lower edges of said sheath are sewed or otherwise suitably secured to a leather strap, K, of a thickness greater than that of the sheath k , and equal, or nearly so, to that of the traces,

said strap being arranged in rear of the hame-tug sections.

By means of the peculiar construction of tongue and socket heretofore described, a minimum of wear from said connection between the sections is brought upon the leather sheath *k*, which was the principal objection to the device shown in my application hereinbefore referred to, and to other constructions 10 at present in use.

By lessening or decreasing the wear and friction upon the sheath it is rendered more durable, and will consequently last much longer and reduce the cost of the device.

15 The trace-carrier *C* is provided with a tongue, *C'*, similar in construction to the tongue of the sections, said tongue engaging one of the section sockets.

L designates a hame-plate having a socket, 20 *l*, at one end to engage a tongue of one of the sections *B*, and having a longitudinal groove, *l'*, at its other end, between the flanges *l''* of which is adapted to be secured a hook adapted to connect the said plate to a hame, apertures *l'* being provided for the passage of rivets or screws to fasten the hook to the plate.

Having thus fully described my invention, what I claim as new, and desire to secure by Letters Patent, is—

25 1. A hame-tug comprising a series of sec-

tions flexibly and detachably connected together, each section having a socket provided with lateral seats *f'* at one end, and a projecting tongue *g* at its opposite end, and provided with lateral tapering flanges, the tongue and flanges of one section engaging the socket and seats, respectively, of the adjacent section and lying flush with exterior faces thereof, substantially as described. 35

2. A hame-tug comprising a series of sections flexibly and detachably connected together, a trace-carrier, and a hame-plate detachably connected to the sections, and the whole inclosed within a sheath, each plate or section of the tug having at one end a socket 40 with lateral seats, *f'*, and a lower brace or cross-bar, *f''*, at its extremity, and at its opposite end a contracted projecting tongue, *g*, having a lug, *h*, and forwardly-inclined lateral lugs *i j*, the tongue and its lugs of one 45 section engaging the socket and seats of the adjacent section and lying flush with the exterior faces thereof, substantially as described.

In testimony that I claim the foregoing as my own I have hereto affixed my signature in 50 presence of two witnesses.

THOMAS L. RIVERS.
